UNITED STATES PATENT OFFICE

1,948,853

MAGNETO CONSTRUCTION

William C. Heath, Milwaukee, Wis., assignor to
 Fairbanks, Morse & Co., Chicago, Ill., a corporation of Illinois

Application August 29, 1932. Serial No. 630,873

4 Claims. (Cl. 171—252)

This invention relates to improvements in magneto construction, and more particularly to improvements in rotors of magnetos of the type employing rotating permanent magnets.

5 In certain prior types of magnet rotors, it is usual to employ a mass of cast non-magnetic metal, such as brass, for the rotor shaft, and for intimately uniting the laminated pole shoes. Such structures are objectionable, in that a cast 10 shaft is comparatively low in tensile strength and rigidity, and is needlessly expensive for shafting material. In magnetos of this type, it is desirable to employ permanent magnets formed of cobalt steel or other materials having high magnetic 15 retentivity. Such materials have not been widely used in magnetos, because of the difficulty experienced in machining, and in securing the pole pieces to the rotor. In prior types of rotor constructions it is usual to employ screws or other like 20 fastening means for securing the permanent magnets and the various other parts to the rotor shaft. Such constructions are objectionable in that the screws are very likely to become loose and ineffective after a period of use.

25 An object of the present invention is to provide an improved rotor for magnetos of the type noted, which includes a rotor shaft formed of steel or other similar material, and a mass of die-cast aluminum or zinc alloy for structurally 30 uniting the laminated pole shoes to the shaft. By this provision, a shaft of substantial strength and rigidity is employed in the rotor assembly.

35 A further object is to provide an improved rotor construction in magnetos of the rotating field type, which includes a mass of die-cast non-magnetic metal for securing the laminated pole shoes to the rotor shaft, individual masses of non-magnetic metal for securing suitable bridging members to the pole pieces, and means for 40 removably securing the pole pieces and associated bridging members into intimate contact with the pole shoes.

45 A still further object is to provide an improved rotor for magnetos of the rotating field type, in which the laminated pole shoes are firmly assembled with the rotor shaft by means of a mass of die-cast non-magnetic metal, and in which the pole pieces and bridging members are removably 50 assembled and more firmly secured to the die cast mass, than is possible through the use of screws, bolts, nuts or like separate fastening and holding elements.

55 An additional object is to provide an improved rotor for magnetos of the rotating field type, which is rigid and durable in construction, and

is composed of but a few simple and easily assembled parts, and which results in a substantial reduction of production costs, through minimization of machining operations on the permanent magnets.

Further objects and advantages will appear from the following detailed description of parts, and the accompanying drawing of a simple preferred embodiment, and in which:

Fig. 1 is a longitudinal section of a preferred 65 form of rotor for magnetos of the rotating field type, the section being taken along line 1—1 of Fig. 3; Fig. 2 is a section taken along line 2—2 in Fig. 1; Fig. 3 is a section taken along line 3—3 in Fig. 1; Fig. 4 is a fragmentary section 70 taken along line 4—4 in Fig. 3; Fig. 5 is a section taken along line 5—5 in Fig. 1; Fig. 6 is a fragmentary section taken along line 6—6 in Fig. 5, and Fig. 7 is a fragmentary section taken along the line 7—7 in Fig. 6.

Referring by reference characters to the drawing the numeral 10 designates, generally, a preferred form of rotor for magnetos of the rotating field type, and which includes a rotor shaft 11 formed, by preference, of mild steel or other similar shafting material of substantial strength and rigidity. A plurality of pole pieces or permanent magnets 12 are, by preference, arranged in spaced relation and substantially parallel to each other, and to the longitudinal axis of the shaft. These 80 pole pieces are, by preference, formed of cobalt steel or other material possessing high magnetic retentivity, and are formed, by preference, of a circular cross section to facilitate machining operations. In the preferred example shown, the 85 rotor 10 includes four such pole pieces, although it will be understood that the number may be varied, depending upon the type and number of poles of the magneto to be constructed.

A pair of bridging members 13 of stamped soft 90 iron or steel, are disposed near one end of the rotor and each in contact with the end portions of a pair of the pole pieces 12 of opposed polarity. Each bridging member forms a flux path between the paired pole pieces of opposite polarity, 100 to provide a structure which is, in effect, a permanent magnet of U shape or horseshoe type. By this arrangement there are provided two distinct magnetic circuits within the rotor, where a two pole machine is desired. Each bridging member 105 13 is provided with an intermediate semi-circular recessed portion 14. By reason of this construction, there results an annular space 15, which separates the shaft 11 from the opposed recessed inner margins of the members 13. Pole shoes 16 110

are provided, and consist of stacks of soft iron laminations each of partly sector shape, which are arranged, respectively, on the free ends of the pole pieces 12, each pole shoe connecting the 5 pole pieces of like polarity. Each lamination is, by preference, provided with a pair of apertures 17 which are slotted as indicated at 18, the pole pieces extending through these apertures. It will be readily seen that the pole shoes 16 only 10 partially encircle each of the paired pole pieces, because of the shape and formation of the slotted portion 18 of the laminations.

In assembling the rotor, the laminated pole 15 shoes and rotor shaft, are suitably positioned in a die-casting mold, the mold, prior to casting, being provided with cores corresponding in size and shape with, and so as to result in openings 20. In similar manner, paired, tapered transverse slots 21 are provided by suitable cores in the 20 die-casting mold. A mass of non-magnetic metal 22, such as a suitable aluminum or zinc alloy, is then poured into the mold for intimately uniting to the shaft, the assembled pole-shoe laminations. After the die-casting process, the resulting 25 rigid, integral structure is removed from the mold, and the cores corresponding to openings 20 and slots 21, removed from the casting. The body of cast metal, thus formed, serves securely to embrace the laminations constituting the pole 30 shoes 16, and is provided with peripheral channels 20 therethrough, extending parallel to the shaft, but substantially spaced therefrom, these openings serving, as will hereinafter appear to receive the pole pieces 12.

The pole piece assembly in the preferred example shown, may, if desired, be constructed entirely separately from the body of cast metal containing the shaft and pole shoes. The magnets, or pole pieces are, by preference, peripherally 35 grooved or channelled near one end as indicated at 23. Prior to casting, the pole shoes are disposed in spaced parallel relation, as suggested in Figs. 2 and 3, with their correspondingly grooved ends extending into a suitable die casting mold 40 which may be substantially smaller than that employed by the body of metal 22, the mold for the pole piece assembly serving to contain, prior to casting, the desired number of bridging elements 13 arranged for example, as suggested in Figs. 5 and 6. Cast metal 24 is then poured about 45 the bridging pieces 13 and the adjacent grooved ends of the pole pieces, so as firmly and permanently to unite, and magnetically connect, the end faces of the pole pieces to the bridging elements therefor. The cast structure, including the 50 body of metal 24, firmly embraces the bridging member 13 and the ends of the pole pieces, as will appear as shown in Figs. 1 and 6, it being noted that each body of metal 24 is provided with opposed recessed portions 25, so that after application 55 of the pole assembly to the remaining elements heretofore described, the single steel shaft 11 projects endwise of and beyond each of the opposite ends of the assembled rotor as shown in Fig. 1. Assembly of the several parts embraced, 60 respectively, by the bodies of metal 24 and 22, may be effected by inserting the pole pieces endwise into the openings 20 therefor to an extent sufficient to bring the pole pieces through both the cored openings 20 and the pole shoe apertures 17. It will be noted (Figs. 3 and 4) that each pole 65 piece is provided with a slotted or notched portion 26 which, in assembly, are brought into register with the transverse slots 21 previously cored in the body of metal 22.

With the parts in this position, a tapered wedge pin 27 is driven or pressed into each slot therefor so as snugly to engage the walls of the corresponding passage 21 and at the same time wedgingly engage at least a pair of seats 26 in the pole pieces. The wedge pins 27 may be formed of a suitable non-magnetic material and, as illustrated, each of such pins serves to position a pair of the pole pieces of opposite polarity, in the assembly.

80

35

The rotor is now completely assembled and ready for use in a magneto, and it will be apparent that by the above arrangement all screws or threaded fastening means for assembling the rotor, are eliminated, a much simpler and more secure assembly expedient being provided by the wedge pins.

90

In the construction above described, it will be seen that the mass of cast, non-magnetic metal secures the various parts of the rotor to the shaft, and that a web of non-magnetic metal, magnetically insulates the bridging members 13 from the shaft. The tapered slots 21 are, by preference, formed with a tapered wall portion 30 and an opposite straight wall portion 31. By 100 this provision, the slots in the pole pieces may be ground without taper to facilitate machining and assembling. It will be readily seen that the entire pole piece assembly, including a pair of the pole pieces 12 and the bridging member 13 therefor, may be removed, as a unit, for remagnetizing purposes, simply by withdrawing the wedge pins 27. After remagnetization, the poles may be reinserted and again secured in place by the pins 27. The use of these wedge pins eliminates expensive and difficult machining operations on the hard steel magnets. The only operation, viz., that of grinding the straight slots 21 and grooves 26, is simple and inexpensive, as compared to the machining necessary with prior types of rotors.

105

By reason of simplifying the description of a single embodiment of the invention, the drawing shows an arrangement in which only two pole pieces of opposite polarity are held in assembly including a bridging element cast into the body 115 of metal 24. It will appear that the body of metal 24 may be formed to embrace the ends, say, of four or any other desired number of the pole pieces so as to enable their application to, and removal from the body 22, as a unit. While the 120 present drawing illustrates the rotor for a two-pole machine, by the expedient last described the rotor may be formed suitably for either a two or four-pole machine, or a machine having any other usual and desired number of poles.

115

The rotor shaft 11 is, by preference, provided with a knurled portion 32 to insure good interengaging coherence between the mass of cast metal 22 and the shaft. This knurled portion prevents any relative movement, due to an improved bond between the cast metal 22 and the shaft. It will be apparent that the present improved rotor is neat and compact in construction, and forms practically a rigid, solid, rotating mass.

120

It will, of course, be understood that the present 135 detailed description of parts and the accompanying drawing relate only to a single preferred executional embodiment of the invention, and that substantial changes may be made in the described arrangement and construction of parts without departing from the spirit and full intended scope of the invention.

135

I claim:

1. A magnet structure for magnetos of the rotating-field type, including a shaft, pole shoes 140

150

spaced from said shaft, a body of non-magnetic metal cast about a portion of the shaft and the pole shoes, the pole shoes and body of cast metal having preformed longitudinal openings, arranged to receive a plurality of pole pieces; an assembly of parallel pole pieces including an element bridging a plurality of the pole pieces near one end thereof, a second body of non-magnetic metal cast about the bridging element and adjacent ends of the pole pieces engaged thereby; the pole pieces and the first named body of cast metal having preformed openings, and locking pins extending through the openings in the first named body of cast metal and said pole pieces for securing the assembly thereof in predetermined detachable relation to said first named body of cast metal and the pole shoes.

2. In a magnet structure for magnetos of the rotating-field type, a rotor shaft, a body of non-magnetic metal cast onto said shaft, pole shoes carried by said body, the pole shoes and body having openings formed therein arranged to receive a plurality of pole pieces, disposed parallel to the shaft; an assembly of pole pieces having peripheral grooves near their corresponding ends, a bridging member engaging the ends of the pole pieces, a body of non-magnetic metal cast about the bridging element and the grooved ends of the pole pieces for securing them in assembled relation, and means for securing the pole piece assembly to the pole shoe and shaft assembly, said means consisting of transverse tapered channels in the first named body of cast metal and transverse grooves in said pole pieces, and pins of tapered section coacting with said channels and grooves to position the pole piece assembly with respect to the shaft and pole shoe assembly.

3. A magnet structure for magnetos of the rotating-field type, including a shaft of ferrous metal, a body of non-ferrous metal die-cast onto

said shaft, laminated pole shoes carried by said body, a second die-cast body of non-ferrous metal, spaced along the shaft from said first named body, pole pieces and a bridging element therefor, carried by the second named body, the last named body being die-cast into interlocking relation with the bridging element and corresponding ends of the pole pieces, whereby the pole pieces are mounted as an assembled unit, and means for relatively positioning the pole pieces within said first named cast body, said means including tapered transverse passages in the first named body of cast metal, and grooves in the pole pieces, and tapered locking elements disposable in said passages, an interlocking engagement with the grooves in the pole pieces.

4. In a magnet structure for magnetos of the rotating-field type, a pole piece assembly including a plurality of endwise peripherally grooved pole pieces, a bridging element for a plurality of said pole pieces, and a body of cast non-magnetic metal interengaging said grooves and securing the pole pieces in contacting relation with said bridging element; a second body of cast non-magnetic metal, a plurality of laminated pole shoes secured by said second cast body, the pole shoes and second named body having preformed pole-piece openings longitudinally thereof, and a shaft of ferrous metal united, by casting, to one of said bodies of cast metal and projecting endwise beyond both of said bodies, and means for securing the pole piece assembly, into assembled relation with said last named cast body, said means including a preformed tapered bore in said last named body of cast metal, and grooves in said pole pieces, registerable with said bore when the pole pieces and said last named body are in assembled relation, and tapered pins disposable in the bore and grooves, to secure the pole pieces and pole piece assembly against endwise movement.
